C. E. & I. J. BISHOP.
CONDENSER FOR STEAM ENGINES.
APPLICATION FILED MAY 12, 1913.

1,205,701.

Patented Nov. 21, 1916.

UNITED STATES PATENT OFFICE.

CARL E. BISHOP AND IRA J. BISHOP, OF MITCHELLVILLE, IOWA.

CONDENSER FOR STEAM-ENGINES.

1,205,701.

Specification of Letters Patent. Patented Nov. 21, 1916.

Application filed May 12, 1913. Serial No. 767,225.

To all whom it may concern:

Be it known that we, CARL E. BISHOP and IRA J. BISHOP, citizens of the United States, and residents of Mitchellville, in the county 5 of Polk and State of Iowa, have invented a new and useful Condenser for Steam-Engines, of which the following is a specification.

The object of our invention is to provide 10 a condenser of simple and comparatively inexpensive construction, for steam engines.

A further object is to provide such a condenser whereby substantially all of the steam passing through the cylinders may be 15 condensed and used again.

Still a further object is to provide such a condenser in which steam passing from the exhaust ports of the cylinder is carried through a number of tubes in which a considerable surface is exposed to radiation 20 from the air and in which the steam remaining uncondensed is passed through water, whereby the condensation is completed.

Still a further object is to provide such 25 a condenser provided with a receptacle for any surplus steam which may possibly have passed through said water.

A further object is to provide a condenser 30 of comparatively small and light construction and provided with a water supply receptacle to receive the water of condensation from the radiator, and further to act as a heat storing device to absorb the heat from the steam that passes through the radiator 35 when the engine is carrying a load that is greater than normal, and in connection with this water receptacle to provide radiating devices to radiate the heat that has been stored at the time that the engine was carrying 40 this heavy load; and further to provide in connection with this water receptacle an auxiliary radiator to condense the steam that is formed by the hot water within the receptacle.

Our invention consists in certain details, 45 in the construction, combination and arrangement of the various parts of the device, whereby the objects contemplated are attained, as hereinafter more fully set forth, 50 pointed out in our claim and illustrated in the accompanying drawings, in which,

Figure 1 shows a side elevation of an 55 engine and condenser, embodying our invention, parts of the device being shown in vertical cross section. Fig. 2 shows a front elevation of an air radiator, and Fig. 3 shows

a front elevation of a portion of a water radiator and the pipes leading thereto and therefrom.

Our improved condenser is especially designed to be used in connection with an engine for automobiles. We have, therefore, in the accompanying drawing, used the reference numeral 10 to indicate generally the hood of a motor car. Suitably supported upon the frame of the machine, where the device is used with automobiles, is a boiler 11.

We preferably use our improved condenser in connection with our automatic water and fuel control, as disclosed in our 70 application for Patent No. 761,364, filed April 15, 1913.

For purposes of illustration we have shown an engine cylinder 12 connected with the boiler 11 by a pipe 13, in which is a suitable valve 14, controlled by a lever 15. A crank shaft 16 is operated from the piston rod 17 by means of a pitman 18. Operatively connected with the piston rod is a pump 19, the operation of which will be hereinafter more fully explained. Leading from the exhaust port of the cylinder is a pipe 20 through which the exhaust steam passes to the radiator 21, which comprises the receptacle or chamber, clearly shown in Figs. 1 and 2. The radiator 21 is provided with a plurality of tubes or openings 22 passing through from front to back, as clearly shown in said figures. The tubes 22 permit the passage of air, thereby affording a considerable surface for 90 radiation. It will readily be seen that a considerable part of the exhaust steam will be condensed in the radiator 21.

Leading from the lower part of the air 95 radiator 21 are a plurality of vertical tubes 23, designed to be fully exposed to the air. Considerably below the level of the radiator 21 is a water supply tank 24 comprising a receptacle having a plurality of tubes 25 extending through from front to back for permitting the passage of air for cooling water in the water receptacle 24.

Connected with the lower ends of the tubes 23 are slightly larger tubes 26 which may be arranged at different heights and of 105 different lengths. Part of the tubes 26 may enter the water receptacle 24 near the upper part thereof and extend toward the rear part of the interior of said receptacle. Some of the tubes 26 may enter said receptacle below the upper tubes 26 and extend toward the middle of the interior of said receptacle,

as shown in Fig. 1. The lower tubes 26 may simply enter the water receptacle 24. On account of this arrangement most if not all of the steam in the tubes 26 will be condensed before reaching the surface of the water. Owing to the arrangement of the tubes 26, the steam which enters the receptacle 24 near the surface of the water therein, is carried a considerable distance in the pipes 26 before it is discharged into the water, and the steam from the shorter pipes 26 is discharged deeper in the water so that all is likely to be condensed before rising to the surface of the water.

15 The radiating surface of the tubes 23 and the radiator 21 are of such dimensions that the steam from the engine, when running at normal speed and carrying a normal load or less, will be condensed by the radiator 21 and the tubes 23. At the same time the water in the receptacle will be cooled to a temperature quite a little below the condensing point of steam. It will be seen that if the load on the engine is increased, or the speed 20 is increased, as when climbing a hill, the flow of steam to the condenser will be increased to such an extent that the radiator 21 and the tubes 23 would not condense all of it. The steam in the tubes 23 would then 25 be forced into the water receptacle where it would be condensed and the heat taken on by the water would be given off at such times when the engine was under a partial load.

30 35 Communicating with the upper portion of the water receptacle 24 are a plurality of vertical pipes 27, preferably of slightly larger diameter than the pipe 26. The pipes 27 communicate at their upper end with an auxiliary radiator 28, comprising a receptacle through which pass a number of tubes 29. It will be understood that the tubes 22, 25 and 29 are open at both ends to allow the 40 passage of air.

45 50 Connected with the receptacle 28 is a stop cock 30 and communicating with the receptacle 24 and extending upwardly therefrom is a pipe 31 for filling the receptacle 24. The pipe 31 is provided with a removable cap 32. Leading from the lower portion of the receptacle 24 is a water pipe 33 which supplies water to the pump 19. A tube 34 leads from said pump to the boiler 11.

55 60 In the practical operation of our improved condenser, the receptacle 24 serves not only as a radiator but as a water supply tank. The pipes and the receptacle 24 are filled to the proper height through the tube 31. Some water is placed in the boiler 11 and 65 heated by means of a suitable burner or the like. The engine is started by means of the throttle lever 15. The exhaust steam from the cylinder passes through the pipe 20 to the radiator 21 and from thence to the pipes 23. The steam is considerably cooled and

some of it is condensed before it reaches the water in the pipes 23.

We believe it to be a fact that when water is pumped from the radiator 24 a slight vacuum is created in the radiator 28. Steam 70 tends to reach the point of least resistance and is drawn through water in the pipes 23 and the receptacle 24. We find it to be a fact that the steam is practically all condensed before it passes from the water in the 75 receptacle 24 although a slight vapor is created in the upper ends of the pipes 27 and in the radiator 28. We have found by experiment that water will condense steam more rapidly than air, but we use the air pipes to 80 insure complete condensation.

It has already been noted that the pipes 26 are slightly larger than the pipes 23 and that the pipes 27 are slightly larger than the pipes 26. The purpose of such construction 85 is to enable the steam more easily to reach the point of least resistance should any vacuum exist in the radiator 28 and to cause the steam to be drawn through the water rather than simply to draw water upwardly 90 in the pipes 27.

An especial purpose of the radiator 28 is to furnish a chamber above the receptacle 24. When the pressure of the steam in the pipes 23 and 26 overcomes the pressure of 95 the water in the receptacle 24, it tends to move through the water in the receptacle 24, toward the radiator 28 or toward the point of least resistance. The radiator 28 may thus be said to furnish a space toward which 100 the steam may pass or move, on its path through the water. When the steam passes into the water in the receptacle 24, it tends to pass upwardly and keeps up a constant movement of the water. At the same time, 105 the steam condenses and adds to the water supply in said receptacle, while some water is being drawn off to the boiler, making a continuous circulation. The tendency of the steam is to pass upwardly to the tubes 27 and on rare occasions some steam may pass 110 to the radiator 28 where it will be completely condensed, thereby saving all the water. Some vapor may rise from the water in the receptacle 24 and such vapor will 115 be condensed in the tubes 27 and the radiator 28.

The advantages of such a condenser as we have hereinbefore described are numerous. Owing to the fact that water condenses 120 steam much more rapidly and completely than air, we are able to use practically the same water for a long period of time, thereby enabling us to use a steam engine driven motor car in sections where it is difficult to 125 get water frequently. On account of the fact that the same water is condensed and again vaporized we are able to use a smaller water supply tank. The weight of our entire plant is very small compared to that of 130

an ordinary steam engine. On account of the fact that few refillings are needed, the deposit of lime is comparatively slight. Of course some steam is lost but a small amount 5 of oil is found to pass with the exhaust steam so that the total bulk of material in the radiator 24 remains substantially the same.

At comparatively long intervals, the 10 water may be withdrawn and filtered to remove the oil, and again used. We preferably use rain water with our boiler where it can be obtained.

It may be noted that the passage of the 15 steam into and through the water in the radiator 24 heats it so that the water supplied to the boiler is much warmer than would ordinarily be the case, thereby enabling us to change the water to steam with 20 a smaller supply of fuel than would otherwise be the case.

In using our plant with an automobile, the warm air passing the condenser parts 25 strikes the boiler 11 and helps to keep it warm, in this way also making it easier to produce steam and making it possible to do so with less fuel than would otherwise be the case.

It will be understood that many variations may be made in the details of the con- 30

struction of our device, and that it is our intention to cover by this application any such variations which may be included within the scope of the appended claim.

We claim as our invention:

In a device of the class described, a receptacle a second receptacle spaced vertically above the first receptacle, tubes connecting the upper and lower receptacles, a discharge tube leading from the lower part 40 of the lower receptacle, a plurality of steam and water carrying tubes mounted in the wall of the first receptacle and extending toward the interior thereof at different heights therein, said last described tube being graduated in length on the interior of 45 said receptacle, the lower tubes being the shortest and the upper tubes being the longest, whereby steam discharged from the lower tube will travel a greater distance 50 upwardly in said first receptacle and reach the top thereof, than steam discharged from said longer upper tube.

Des Moines, Iowa, April 28, 1913.

CARL E. BISHOP.
IRA J. BISHOP.
